UNITED STATES PATENT OFFICE.

LEWIS M. CLEMENT, OF NEW YORK, N. Y., ASSIGNOR TO WESTERN ELECTRIC COMPANY, INCORPORATED, OF NEW YORK, N. Y., A CORPORATION OF NEW YORK.

TELEGRAPH SYSTEM.

Application filed December 5, 1921. Serial No. 519,865.

This invention relates to a telegraph system and more particularly to an arrangement whereby telegraph signals may be transmitted without interference from 5 strays or static.

It has been proposed in carrier wave signaling to employ two sources of different frequency alternating currents within the audible range and to cause these currents to 10 be alternately applied to modify the carrier wave in regular sequence for calling purposes. The transmission station is provided with means to cut off the local talking circuit from the outgoing carrier channel and 15 to connect in its stead to the outgoing channel, a source for alternately applying two alternating currents of different frequency in regular sequence. These alternately applied currents are caused to modify the outgoing 20 carrier wave in the same manner as it is modified by speech currents when carrier telephony is in progress. At the receiving station the modulated carrier wave is detected or demodulated and the detected 25 alternate frequency currents are caused to energize selective circuits to control the operation of a differentially acting relay which in turn operates the local signal element or applies ringing current to the receiving circuit as the case may be.

The present invention has for one of its features the use of waves of different frequencies alternating at a definite rate or shift frequency for telegraph signaling. In signal transmission systems there is frequently 35 a tendency for interference to occur due to static energy or other strays, particularly in certain latitudes and during certain times of the year. In fact, it has been considered 40 practically impossible to free teledynamic operation from interference under the conditions stated above.

According to the present invention a signaling system is provided at its transmission station with means to supply two sets of waves of different frequencies and alternating at a definite rate or shift frequency to constitute signal impulses. The sets of waves may be either high frequency waves 45 adapted to be radiated, low frequency waves designed to modulate a carrier wave, the modulated high frequency wave being transmitted, or low frequency waves which may be transmitted over a line.

At the receiving station the incoming

waves of different frequencies are separated by selective circuits or filters and used to produce oscillating currents which are rectified. The rectified impulses, alternating at the definite rate are supplied to means 50 controlling a signal translating device or indicator having associated therewith means selective of the rate of alternation of the impulses. The latter means may be either an element of the translating device tuned to 55 the shift frequency, such as a tuned reed, or a circuit selective of energy of this frequency included in the connections between the control device and the signal translator. The signal translating device may be a telephone 60 receiver. By making the signal receiving device responsive only to the joint action of the signal waves of predetermined frequencies applied at a definite rate of alternation, which should preferably, but not necessarily, 65 be within the audible range, the possibility of false signals being received is remote.

The primary object of this invention is to provide a telegraph system which will be 70 free from interference due to strays or static.

Another object is to provide a telegraph system employing oscillatory currents of two frequencies alternating at a definite frequency or rate to identify the signal impulses constituting messages transmitted 75 between these stations.

A feature is the provision of means whereby incoming signal waves of different frequencies alternating at a definite frequency or rate may control the operation of a signal 80 translating device.

For an understanding of a signal system operating according to this invention and embodying its principles, reference may be made to the accompanying detailed description taken in conjunction with the annexed drawings, in which Fig. 1 illustrates a radio transmitting station adapted to radiate two high frequency waves alternating at a definite frequency; Fig. 2 shows a station 85 designed to transmit waves of one frequency modulated by two waves of different frequencies alternating at a definite rate; Figs. 3, 4, 5 and 6 illustrate different receiving circuit arrangements which may be used with 90 this system, and Figs. 7 and 8 show modified constructions of signal translating devices.

Referring to Fig. 1, there is shown a source of oscillations comprising a pair of three-element electric discharge devices 1 100

and 2 having common input and output circuits 3 and 4, respectively, coupled to the antenna circuit. The input and output circuits of the discharge devices are coupled to the antenna circuit by an inductometer comprising the coils 5 and 5', the latter of which is adjustable. The output circuit 4 includes the plate primary winding shunted by variable condenser 4'. In this arrangement, the antenna is the oscillating circuit.

The frequency of the oscillations radiated from the antenna is determined by the constants of the system including the condenser 4' and the inductances of the primary plate winding, the antenna and the mutual induction between the primary plate winding and the antenna circuit.

As thus far described, the arrangement is the invention of another and therefore a complete statement of the theory of its operation is believed to be unnecessary. However, in this arrangement increments of energy are fed back from the antenna circuit to the input of the discharge devices to cause these devices to produce oscillations.

Adjustment of the inductometer coil 5' varies the coupling between the tube and antenna circuit and, to some extent, the tuning of the antenna circuit, while the variable condenser 4' serves both to accurately determine the frequency of the waves radiated and to increase the power output of the oscillations generated.

The oscillator herein shown differs from that briefly described above in that an alternating current source 6 is coupled by a transformer 7 to the input and output circuits of the tubes 1 and 2 in such a manner that, as the plate circuit of one discharge device is supplied with potential of the proper sign and value, the corresponding circuit of the other discharge device is reversely connected. Because of the unidirectional properties of these devices, the former will be active to supply increments of energy to the antenna circuit, while the other will be blocked or inoperative. Hence, the antenna circuit, which is the oscillatory circuit of the system, will be continuously supplied with energy by the alternate operation of the discharge devices to set up oscillations of a single frequency in this circuit. The transformer 7 is provided with an additional secondary winding 7' adapted to supply heating current to the filaments of both tubes.

The antenna circuit, in addition to the ordinary tuning means, has associated with it a means for alternately changing its natural period. While this may consist of an inductance or capacity included in the antenna circuit or associated with it in any well-known manner and adapted to be alternately short-circuited by an interrupter to control the periodicity of this circuit, it is herein shown as an inductance coil 8 in-

cluded in the antenna circuit and coupled to a coil 9.

Coil 9 is included in the plate circuit of a discharge device 10. The input circuit of the device includes a source of energy 11 adapted to be controlled by an interrupter 12, for example, a commutator, at a definite rate to thereby alternately impress positive and negative or different negative potentials upon the grid of the device 10 to thereby change its impedance and, as a consequence, vary the loading effect of the coil 8. In this manner the natural period of the antenna circuit is alternately changed at a rate determined by the interrupter 12.

If the commutator is designed and rotated to apply positive and negative or different negative potentials to the control element of the device 10 five hundred times per second, the tuning of the antenna circuit will be changed and hence waves of two different frequencies alternating at this rate will be radiated.

A controller consisting of a relay, key, or other similar device may be included in the oscillator circuit system or a circuit associated with the antenna circuit to control the transmission of signal waves. For example, a key or relay armature 13, may be inserted in the circuit of source 11, in the grid circuit of the oscillator, or in the input circuit of the device 10, for this purpose.

Obviously a discharge device having a single filament, two anodes and two control electrodes may be used instead of the pair of devices 1 and 2 shown in this figure. Moreover, any other high frequency source adapted to be controlled to vary the frequency of the waves supplied by it or, in fact, any other double-frequency source, which may be controlled at the desired shift frequency rate, may be utilized as an alternate-frequency source. Again, any rate of alternation of the two signaling frequency waves may be used, though it should preferably, but not necessarily, be within the range of audibility.

Referring to Fig. 2, an alternate-frequency source 14, consisting of a three-element electron discharge oscillator 15 having alternating current plate and grid circuits coupled in feed-back relation by the transfer 16 is provided. The frequency of the oscillations produced is largely determined, in a well-known manner, by the tuning of the closed circuit including the secondary winding of the transformer 16 and the capacity 17. An additional condenser 18 is arranged to be connected in parallel with the element 17 to change the tuning of this circuit, and in consequence thereof, to change the frequency of the alternating current produced. A vibrator or interrupter, herein shown as a commutator 19, included in the parallel circuit containing the condenser 18

is adapted to be driven to open and close this circuit at a definite rate, and as a result two alternating currents of different frequencies changing at a selected frequency 5 rate will be produced.

As in the arrangement described above the interrupter will be designed and actuated to vary the tuning of this oscillator 15, by the introduction of the condenser 18, five hundred times per second. With the condenser 17 alone in the resonant circuit, the oscillator will supply an alternating current of one frequency, for example, 2500 cycles and with the condenser 18 connected a current of another frequency, for example, 2000 cycles will be provided. While the frequencies for the modulating source are given above as within the audible range, it may be stated 15 that they are not limited to such range.

The plate circuit of the oscillator is coupled by a transformer 22 to the grid-filament circuit of a three-element electric discharge modulator 20, which also includes a source of high frequency current 21. The secondary 25 of the transformer 22 has a condenser 23 connected in parallel with it to constitute a circuit tuned broadly to the frequencies supplied by the oscillator 15.

The plate circuit of the modulator 20 is 30 associated with the input circuit of an amplifier 24, which is merely symbolic of the fact that amplification is desirable, and hence any amplifying system including any number of amplifiers may be used. The output 35 circuit of the amplifier is associated with the antenna 25.

As described above, a key, relay, or other well-known controller 13 may be inserted in the oscillator circuit system, herein shown as 40 connected in the parallel circuit including the condenser 18 and commutator 19, to control the signal energy radiated from the antenna 25.

Fig. 3 shows a receiving station for use 45 with the transmitting station illustrated in Fig. 1 having two receiving circuits associated with an antenna circuit. The antenna circuit 26 is given two degrees of freedom and includes two inductance coils 27 and 28. These coils are respectively associated with 50 tuned circuits 29 and 30 included in the input circuits of two detectors 31 and 32, each of which is also supplied with high frequency currents by the local sources 33 and 34. These sources each supply oscillations 55 of a frequency differing from the incoming waves by a frequency within or without the audible range, for example, 1000 cycles per second.

Thus, if the incoming frequencies are f^1 and f^2 , the source 33 will supply a current of frequency $f^1 \pm 1000$ and the source 34 will supply a frequency of $f^2 \pm 1000$ and as a result there will be present in the output 60 circuits of the detectors 31 and 32 impulses of

the difference frequency, namely, 1000, alternating at a shift frequency determined by the interrupter or commutator 12 of the transmitting station. These impulses, after amplification by the amplifiers 35, are rectified by the unidirectional devices 37. The rectified impulses, succeeding each other at the shift frequency, are transmitted through separate primary windings of the transformer 38 to induce current in its secondary, 70 which is shunted by a condenser 39 to constitute a circuit tuned to the shift frequency.

The primary windings of the transformer 38 should be so connected that impulses supplied to them, if of the same amplitude and applied simultaneously, would not produce a voltage across its secondary winding. On the other hand, signal currents supplied to these windings alternately at the shift frequency of the transmitter interrupter will 80 set up an alternating voltage of this frequency in the turned circuit constituted by the transformer secondary winding and the condenser 39. This voltage will be impressed upon the grid element of the device 40 and because of the amplifying properties of the device 40, a current of large amplitude will flow through its plate circuit which will be transferred by the transformer 41 to 85 the signal receiver 42.

If a disturbance due to strays or static is received, circuits 29 and 30 will probably have oscillations of their natural frequencies set up in them and currents will flow simultaneously through both primary windings 100 of the transformer 38. These currents will balance one another and will produce no effect in the receiver. However, should any unbalance occur, the receiver will not be actuated unless a voltage of the shift frequency, to which the selective circuit included in the input circuit of the tube 40 is 105 tuned, is produced in the secondary winding of the transformer.

A slightly different circuit arrangement 110 for a receiving station of this type is shown in Fig. 4. This arrangement is adapted for use with a system employing two waves of different radio frequencies closely spaced in the frequency spectrum, and a single local 115 source is employed to produce the beat frequency impulses.

In this system two sets of radio frequency waves, which may be of the order of 310,000 and 300,000 cycles, are transmitted from the 120 distant station. At the receiving station, antenna 43 is tuned to receive both sets of waves which are transferred to the input circuit of the detector 44 by the transformer 45, the secondary winding of which is shunted 125 by a variable condenser to constitute a circuit tuned broadly to the same band of frequencies as the antenna.

Associated with the input circuit of the detector is a source of local oscillations 46 130

supplying oscillations of say 250,000 cycles. There will, therefore, be present in the output circuit of the detector 44 oscillations of the difference frequencies 50,000 and 60,000 cycles which may be selected by the tuned circuits or filters 47 and 48, respectively, separately impressed upon the input circuits of the amplifiers 49 and 50, rectified by the unidirectional devices 37 and transmitted to the receiver circuit as described above. Since the selected waves alternate at the shift frequency, an alternating current of this frequency will be supplied to the receiver 42.

Another method of utilizing radio frequency waves to produce an alternating current of shift frequency in the receiver circuit is shown in Fig. 5. In this figure, there is shown a receiving station which embodies an antenna system 53 having two degrees of freedom and a pair of separate tuned circuits or filters 54 and 55 associated therewith, selective of the two sets of high frequency waves.

The incoming waves are selected by the tuned circuits or filters 54 and 55, amplified by the amplifiers 56, rectified by the rectifiers 37, the circuit terminals A and B of which are connected to the correspondingly lettered terminals in this figure, and supplied to the receiver circuit 38-42 hereinbefore described.

As in the preceding arrangements the incoming waves alternate at the shift frequency rate and as a consequence the rectified impulses produce an alternating current of the shift frequency in the receiver circuit to operate the translating device 42, which may translate the signal into sound either by the use of a telephone receiver or a rectifier and relay controlling an ordinary telegraph sounder or other signal translator. For example, a rectifier and relay may be connected in the secondary circuit of the transformer 41, the armature of the relay being adapted to control a local circuit including a sounder.

Referring now to Fig. 6, there is illustrated a receiving station adapted for use with the transmitting station shown in Fig. 2. The incoming signal modulated waves incident upon the antenna 58 are detected by the three-element electric discharge device 59; the detected impulses of the alternate frequencies are amplified by the amplifier 60, separated by the selective means 61 and 62 and rectified by the unidirectional devices 37. The resulting impulses, alternating at the shift frequency, are transmitted to the receiver circuit to set up in the resonant circuit included therein an alternating current of this frequency, which as described above is used to energize the signal translating device 42.

An alternative design of signal translating device is shown in Fig. 7. In this figure

a polarized telephone receiver 65, has its diaphragm 66 connected by a link 67 to a reed 68, tuned to the shift frequency and adapted to be controlled by the energization of the coils 69 and 70. These coils are mounted on the pole pieces of a core 71 and are respectively connected to the points A-A and B-B of the receiving station circuits. Hence, upon the energization of the coils 69 and 70 alternately at the rate determined by the tuning of the reed 68, which corresponds with that of the interrupter or commutator of the transmitting station, this translating apparatus will be actuated to indicate signals.

In Fig. 8, an arrangement including balanced electron discharge devices is shown which may be substituted for the signal translator or receiver circuit arrangement previously described, by connecting the points A and B of the input circuits of the devices 73 and 74 with the correspondingly lettered points in the receiving station circuits.

When no signals are being received, the potential across the plate circuits of the tubes 73 and 74 is supplied by a common battery and hence equal currents will flow in these circuits without affecting the receiver 42. Incoming groups or trains of signal waves of one signal frequency will change the potential applied to the control element of the device 73 and thereby cause variation in the current flowing in its plate circuit. Similarly, trains of waves of the other signal frequency will effect a change in the potential applied to the control element of the device 74 and consequently vary the current flowing in its plate circuit. Under the control of the transmitter interrupter, these current impulses will occur alternately in the output circuits of the devices 73 and 74 at the shift frequency rate to which the circuit 75 associated therewith is tuned, and hence an alternating current of the shift frequency will be set up in the circuit 75. This circuit is included in the input circuit of an amplifier 76, in the output circuit of which the receiving device 42 is included.

Receiver arrangements of the design shown in Figs. 7 and 8 may be substituted for that shown in Fig. 3, since they will only be energized when signal waves of predetermined frequencies recurring at the selected shift frequency are employed.

From the preceding description it will be seen that the signal translating device can only be actuated when signal waves of selected frequencies and alternating at a definite rate are incident upon the antenna. Oscillations set up in the antenna circuit at the receiving station by static disturbances will either balance one another or their rate of alternation will differ from the shift frequency, and, as a consequence, they will not

actuate the receiving device. Again, under any given operating conditions, interfering stations would have to employ not only the same wave frequencies to identify signal impulses, but these waves must also recur at the shift frequency rate.

The last mentioned type of interference, should it occur, may be readily eliminated by varying one of the signal frequencies employed or by varying the rate at which these frequencies are alternately transmitted. In the first case a corresponding adjustment will have to be made in the selective circuits at the receiver station, while in the latter, the tuning of the receiver control element will have to be adjusted to correspond with the new shift frequency used.

Furthermore, though the preferred shift frequency rate is herein stated to be within the range of audibility, it is not necessarily so limited, since, as is well known, waves alternating at an inaudible frequency may be used to control the supply of audible frequency current to the signal translating device at the receiving station.

While certain specific details and elements have been described with the object of clearly and completely disclosing the principles of the invention, and its application to radio telegraphy has been disclosed, it will be appreciated that the principles utilized are independent of the means herein shown and described and therefore they may be applied to low frequency carrier or radio frequency systems. It is therefore to be understood that this invention is not limited to the arrangement herein disclosed but only by the scope of the attached claims.

What is claimed is:

1. A telegraph system comprising means for transmitting signal waves of different frequencies alternately recurring at a definite frequency, means at the receiving station for producing wave trains of different frequencies differing from the incoming waves, and means for producing from said wave trains an alternating current of said definite frequency.

2. A system in accordance with claim 1 comprising a sound producing indicator operated by said last mentioned current.

3. A telegraph system comprising means for transmitting signal waves of different frequencies alternately recurring at a definite frequency, means at the receiving station for producing wave trains of frequencies different from the incoming waves, and means controlled by the joint action of said wave trains for producing an alternating current of said definite frequency.

4. In a signaling system employing a carrier wave modified by non-simultaneous wave trains recurring in regular sequence,

means for deriving from an incoming carrier wave said non-simultaneous wave trains recurring in regular sequence, and means for producing from said wave trains an alternating current of the same frequency as the rate of recurrence of said wave trains for controlling an indicator.

5. A signaling system, utilizing a carrier wave modified by alternately recurring wave trains, comprising a carrier wave circuit, a low frequency circuit, said carrier circuit comprising means for detecting carrier waves received thereover to derive said alternately recurring wave trains, and means for producing in said low frequency circuit an alternating current of the same frequency as the rate of alternation of said wave trains.

6. In a signaling system, means for transmitting a carrier wave, means for modulating said waves at a plurality of frequencies in cyclic order at a definite period of cyclic recurrence, in combination with a receiver selectively responsive to the carrier frequency and each of the plurality of frequencies, a low frequency circuit, and means for producing in said low frequency circuit an alternating current of the same frequency as the cyclic recurrence of said plurality of frequencies.

7. A carrier telegraph system comprising means for transmitting a high frequency wave modulated by waves of different frequencies successively applied at a definite frequency, means for receiving said modulated wave and deriving therefrom said waves of different frequencies, means for selecting said waves of different frequencies, a low frequency circuit, and means, controlled by said waves of different frequencies, for producing in said low frequency circuit an alternating current of said definite frequency for controlling an indicator.

8. A carrier telegraph system comprising means for transmitting a high frequency wave modulated by waves of different frequencies applied alternately, means for receiving said modulated wave, means for detecting and separating said waves of different frequencies, a low frequency circuit, means for producing in said low frequency circuit a current of the same frequency as the rate of alternation of said waves of different frequencies, a sound producing indicator, and means for controlling said indicator by the current in said low frequency circuit to produce a tone of corresponding frequency.

In witness whereof, I hereunto subscribe my name this 29th day of November A. D., 1921.

LEWIS M. CLEMENT.
